UNITED STATES PATENT OFFICE.

GEORGE H. SPAULDING, OF CHICAGO, ASSIGNOR TO WILLIAM DEERING, OF EVANSTON, ILLINOIS.

GRAIN-BINDER.

SPECIFICATION forming part of Letters Patent No. 374,434, dated December 6, 1887.

Application filed October 19, 1886. Serial No. 216,684. (No model.)

To all whom it may concern:

Be it known that I, GEORGE H. SPAULDING, a resident of Chicago, in the county of Cook and State of Illinois, have invented certain 5 new and useful Improvements in Grain-Binding Machines, of which the following is a specification.

This invention has reference to that class of grain-binding machines in which the vibrating 10 needle or binder arm, rising through the deck or binding-table against the gavel, is opposed by a vertically-movable compressor, which falls at the proper time to permit the discharge of the bound bundle from the table thereover 15 in the same general manner as in machines of the well-known "Appleby" type.

The invention relates to improved means for tripping the binder driving-gear into action through the instrumentality of the gavel, and 20 to improved means for controlling the operation of the compressor.

As the breast-plate overlying the grain-passage, the tying mechanism, and the various other parts common to binding-machines of 25 this type may be of ordinary construction and are foreign to the present invention, they are omitted from the drawings, which illustrate only those parts which have connection with the invention.

30 In the accompanying drawings, Figure 1 represents a rear end elevation of the principal parts of a binding-machine having my improvements embodied therein. Fig. 2 is a bottom plan view of the same. Fig. 3 is a top 35 plan view of the pitman and tripping devices through which the binder driving-gear is controlled. Fig. 4 is a rear elevation of the same. Fig. 5 is a rear elevation of the binding-needle, the compressor, and the devices operating directly therewith. Fig. 6 is a rear elevation of 40 the pivoted dog or cam used to control the compressor. Fig. 7 is an edge view of the same and of the needle on which it is mounted, the parts being shown partially in section. Fig. 8 45 is a rear side elevation of the needle. Figs. 9 and 10 are respectively a lower edge view and a rear side elevation of the intermediate arm controlling the compressor. Fig. 11 is a top plan view of the binder deck or 50 table. Fig. 12 is an edge view of the same, looking from the front of the machine. Fig.

13 is a side elevation of one of the spring-bolts by which the binder-deck is secured in position.

Referring to the drawings, A represents the 55 binder-frame, commonly known as the "binder-gear standard," made of substantially the same form as in existing Appleby machines, with a tubular arm, a, underlying the grain-table to receive the needle-shaft, and a second 60 tubular arm, b, overhanging the grain-table to receive the knotter-shaft. The lower arm is bolted to transverse bars or sills B B', which are also bolted, as usual, to a supporting bar or rod, C, lying in a fore-and-aft direction. 65

D represents the binding-needle, of ordinary form, secured, as usual, to a rock-shaft, E, extended through the lower arm, a, of the binder-frame, and provided at its front end with an operating crank, F, fixed rigidly thereon, 70 as usual.

In order to give support to the parts herein-after described, I provide the frame with an extra sill or base-bar, B², at the front. This sill is bolted at one end to and sustained by 75 the rod C, already referred to. At the opposite end it is supported by a sleeve, G, mounted loosely upon the end of the needle-shaft, which is extended for this purpose beyond the needle, as shown in Fig. 2. 80

To prevent the lateral movement of the sleeve and sill B², a pin, c, or equivalent device, is applied to the end of the needle-shaft, as shown.

The extension of the needle-shaft to support 85 the sill is an important feature of my invention.

It is manifest that the form of the sill and its support may be modified at will, provided only they are sustained by the extended end 90 of the needle-shaft.

H represents the packer-shaft, provided, as usual, with cranks to carry the packer-arms. This shaft is mounted in boxes on the sills B B' B², as shown, whereby it receives a firm 95 support and is prevented from springing. The packer-shaft receives a constant motion from a sprocket-wheel, I, mounted thereon and connected thereto by a spline, or equivalent sliding connection, which admits of the wheel remaining at rest as the packer-shaft slides forward and backward in adjusting the binder 100.

upon the harvester. A gear-wheel, J, fixed on the rear end of the packer-shaft, imparts motion to a second gear, K, on a short shaft, L, extended through a bearing bolted to the 5 sill, and provided at the opposite end with a sprocket-wheel, M, which communicates constant motion through a chain, N, to a large wheel, O, mounted to revolve freely on the knotter-shaft P.

10 The shaft P, mounted in the upper end of the gear-standard, will be provided with the usual gear for operating the knotting mechanism and with the arms for discharging the bound bundles. At its rear end the shaft P is 15 provided with a crank, Q, fixed rigidly thereon and connected by a pitman, R, herein described in detail, with the crank F of the needle-shaft.

In order to transmit motion to the needle, 20 I provide clutching devices for connecting the crank Q to the wheel O, whereby the wheel is caused to revolve the crank, which in turn, through the pitman R and arm F, imparts a vibratory motion to the needle-shaft, causing 25 the needle to rise and fall. The clutching devices just referred to, which form an important part of my invention, I will now describe, referring particularly to Figs. 1, 2, and 3.

The wheel O is provided on its side face at 30 regular intervals with a series of studs or rollers, e, which ordinarily travel freely past the side of the crank Q. On the crank, at the point f, there is pivoted a dog, S, having, as shown in Figs. 3 and 4, a lateral projection, g. 35 A spring, h, connecting the dog and the crank, tends to turn the dog upon its pivot in such position that its projection g will stand in the path of the rollers e. When this occurs, the first advancing roller bearing on the projection g will, through the dog, impart motion to the crank Q, the crank, with the dog thereon, revolving with the wheel O, and imparting motion, as before explained, to the needle. In order to stop the motion of the crank, it is 40 only necessary to turn the dog S backward on its pivot against the action of the spring until the projection g is carried out of the path of the rollers, as shown in Figs. 3 and 4, whereupon the crank, being released from the wheel 45 O, will cease its movement, although the rotation of the wheel continues.

The crank is required to make but one revolution during the binding of each bundle. In order automatically to effect its stoppage at 50 the end of this revolution and in a definite position, I construct the pitman in the peculiar manner shown in the drawings. Its main portion consists of a rod, i, continued upward loosely into the pitman-head j, and provided 55 in the slot in said head with a nut, k, one end of which is projected laterally beyond the slot in order to encounter the end of the dog S. A spiral spring, m, encircles the body of the pitman, bearing at one end against a loose 60 collar, n, and at the opposite end against a collar, o, adjustably fixed on the pitman. This 65 spring tends to force the body of the pitman

downward and to hold the nut k in the lower end of the slot, in which position its projecting portion will encounter the end of the dog S 70 as the latter is brought around by the crank, and act to throw the dog backward out of engagement with the roller of wheel O, as shown in Fig. 1.

To start the binder, it is only necessary to 75 force the lower end of the pitman upward, the effect of which is to carry the nut k upward from under the lower bent end of the dog S, which, being thus released, is turned by the spring into position for engagement with the 80 rolls, as heretofore described. The upward movement of the pitman may be caused by devices of any suitable character connected with the needle or with the compressor in such manner as to be affected primarily by the 85 pressure or resistance of the grain. I recommend, however, for this purpose a construction such as shown in the drawings, and which I will now describe.

T represents the compressor, arranged to 90 swing vertically around a horizontal pivot, o', at the lower end of a rigid stationary arm, U, which may be extended downward from the base of the binder-frame, or otherwise supported. The compressor is extended at its 95 heel end beyond the pivot and provided with a lip, p, to encounter the arm U and limit its falling motion, and also provided with a laterally-projecting stud or roller, r, on which a cam on the needle acts to secure the elevation 100 and depression of the compressor at the proper time. The needle is constructed, as shown in Fig. 8, with a web or arm extended downward and rearward, and terminating at the rear end in a portion, s, which acts, when the needle is 105 fully depressed beneath the compressor, as shown in Figs. 1 and 5, to lift the compressor and sustain it in its operative position. On the side face of the needle I form an eccentric 110 flange, t, having a break or interruption at its middle; and in this break, for the purpose of bridging over the space between the two ends of the flange, I pivot near its middle a dog or latch, V, such as shown in detail in Figs. 6 and 7. The journal of this latch formed 115 thereon is extended through the needle, as shown in Fig. 7, and encircled by a spring, v, which tends to hold the latch in the position shown in full lines in Fig. 5.

The operation is as follows: At the instant 120 the bundle is discharged the parts stand in the positions indicated by dotted lines in Fig. 5, the needle being fully elevated and the compressor fully depressed. As the needle retreats, its heel projection s, acting beneath the 125 compressor, carries the same upward to its operative position. During this movement of the parts the roller r on the heel of the compressor rides over the upper side of the pivoted dog V, and finally, depressing the upper end 130 of the dog, passes through beneath the upper end of the flange t on the needle to the position shown by full lines in Figs. 1 and 5, the dog immediately resuming its original position

under the influence of the spring. As the gavel is accumulated by the packers, it exerts a pressure against the compressor T, forcing the same rearward to a slight extent, whereupon 5 the roller r of the compressor, acting on the flange t of the needle, forces the latter slightly upward, the effect being to turn the needle-shaft and its crank f, which latter, through the pitman, trips the binder into action, as before explained. The driving-gear, being set in motion, 10 acts to positively elevate the needle. During this action the compressor T, being relieved from the support of the arm s, is sustained by the roller r, bearing beneath the flange t and 15 dog V of the needle, which travel thereover. Owing to the eccentricity of this flange and dog with reference to the needle-shaft, they act during the elevation of the needle to depress the roller r, and thus force the compressor toward the needle, that it may act the 20 more effectively in the compression of the grain. At the instant the binding operation is completed the advancing needle carries the pivot of the dog V beyond the roller r, where- 25 upon the weight of the compressor causes the roller to pass over and above the tail end of the dog, the compressor falling to the position indicated in dotted lines in Fig. 5 to permit the discharge of the bundle, and the roller assuming such position that it may travel over 30 the top of the dog, as before explained.

From the foregoing it will be understood that the compressor acts first to slightly advance the needle and thereby start the binder, 35 and that the needle in its turn acts thereafter to sustain, advance, and finally release the compressor.

The binder deck or table W is of substantially ordinary form and construction, being 40 divided transversely into two parts, lying one in front and the other in rear of the needle. In order to avoid the troubles incident to the attachment and removal of this table in machines as ordinarily constructed, I adopt the 45 construction shown in Figs. 11 and 12. The upper edge of the table lies upon a stationary supporting-rail, w, as usual, and is provided on the under side with plates x, engaging in or beneath this rail to keep the table from 50 rising. At or near the lower edge the table is provided with dowel-pins y, or a cleat, y', to engage the stationary supporting-bar z, whereby the table is prevented from sliding downward. Spring-actuated pawls a' slide 55 in plates secured to the under side of the table and enter the rail z, thus holding the table down in place. On withdrawing these pawls the table is released, so that it may be lifted and drawn edgewise from the machine.

60 Having thus described my invention, what I claim is—

1. The knotter-driving shaft provided with a crank, the constantly-driven wheel O, revol- 65 lable freely around said shaft, the dog or pawl mounted in the crank and adapted to engage the wheel O, the spring to cause the engage-

ment of the dog, a stop to hold the dog out of action, and the needle-operating pitman connected with said stop to disengage the same from the dog, substantially as described.

70

2. The knotter-driving shaft and its crank, in combination with the independently-revo- 75 lable driving-wheel O thereon, the intermediate dog or clutching device, S, the rock-shaft E, having the needle and the crank F fixed thereon, the longitudinally-yielding pitman R, connecting the needle-shaft crank with the knotter-shaft crank, and a stop connected with said pitman to hold the dog S out of action.

3. The knotter-driving shaft P and its crank, 80 in combination with the loose driving-wheel O, the dog or clutch S between said wheel and shaft, the spring to cause the engagement of the dog, the compressible pitman and the stop connected therewith to hold the dog out of ac- 85 tion, the needle-shaft having the crank con- 90 nected to the pitman, the compressor, and intermediate devices through which the com- 95 pressor in retreating causes a slight advance of the elevated needle, whereby the pressure of the gavel against the compressor is caused to trip the binding mechanism into action.

4. In a grain-binder, the constantly-driven wheel O, the knotter-driving shaft P and its crank Q, and the dog or clutch device S, 95 mounted on the crank, in combination with the spring tending to cause the engagement of the dog, the slotted pitman-head coupled to the crank, the sliding stop k in said head, the pit- 100 man rod or body arranged to slide in the head and actuate the stop, the spring tending to re- 105 sist the sliding motion, and suitable mechan- 110 ism through which the pitman is moved by the pressure of the grain.

5. The pivoted compressor-operating arm 105 having a stud or roller, r, in combination with the vibratory binding-needle having the flanges and the switch V, substantially as de- 110 scribed, whereby the retreat of the compressor under the pressure of the gavel is caused to 115 impart a slight advance of the needle, and the subsequent advance of the needle under the influence of its driving mechanism caused to sustain and finally release the compressor.

6. The pivoted vibratile needle having the 115 eccentric flange, the pivoted dog, and the heel- 120 extension s, in combination with the com- 125 pressor-arm T, pivoted on the frame and pro- 130 vided with a stud or roller, r.

7. The binder-frame provided with the rigid 120 depending arm V, in combination with the compressor-arm T, pivoted to the lower end 125 of said arm and provided with the roller r, the needle-shaft mounted in the frame above the axis of arm T, and the needle having its heel end widened and provided with the eccentric flanges and the pivoted switch to act on said roller, and with the extension s, to elevate the compressor.

8. The binder main frame and the needle- 130 supporting shaft mounted therein and ex- 135 tended beyond the needle and frame, in com-

bination with a sleeve or plate, G, mounted on the overhanging end of said shaft, to sustain other parts of the machine.

9. The binder-frame of the type herein described, the needle, and the needle-operating shaft mounted in and wholly sustained by the lower arm of the frame and extending beyond the same, in combination with sill B² and its support G, sustained through the medium of 10 the shaft from the frame.

10. The binder frame or standard of the type herein described, in combination with the needle, the needle-shaft mounted in the lower arm of the frame, sustained wholly thereby, and 15 extended beyond the needle, as described, the

sill B², and the sill-support G, mounted on the extended end of the needle-shaft and secured against the side motion by a pin or fastening, c, on the shaft.

11. In combination with the binding-table 20 and its supporting-bars, the plates x, attached to the upper edge of the table on the under side, shoulders or stops y, to prevent the edge-wise motion of the table in a downward direction, and the spring-bolts a'.

GEORGE H. SPAULDING.
